UNITED STATES PATENT OFFICE.

LAURENCE M. FOSS, OF WAKEFIELD, MASSACHUSETTS, ASSIGNOR TO MORRISON-SKINNER COMPANY, OF WAKEFIELD, MASSACHUSETTS, A CORPORATION OF MASSACHUSETTS.

METAL-SCREEN-FRAME PULL.

Application filed June 16, 1928. Serial No. 285,837.

In the construction of window screens having metal frames, it is practically necessary, or very desirable to provide a handle on the inner side of the frame by means of which the frame may be raised. The attachment of handles to metal frames of this character, however, present difficulties in several respects, particularly when the frame is made of extruded aluminum alloy, so that soldering, spot welding or rivetting is difficult or impractical, for various reasons, including labor cost and appearance when finished. Moreover, usually the inner side of the frame must slide close to the outer side, of one of the window sashes, usually the upper sash, so that it is usually necessary that the handle be attached in such a manner that no portion of the handle, or its attaching means, projects beyond the inner or face side of the frame.

The object of my invention is to provide a simple and effective means for attaching a handle of the common pull type to a screen frame of metal and particularly of aluminum alloy, so that the handle will not project beyond the inner side surface of the frame and will present a finished appearance, and so that labor cost of making the attachment may be less than, or will not exceed that of constructions previously employed.

I accomplish these objects primarily by providing a handle having transversely enlarged beveled end portions, recessing the inner sides of the lower bar of the frame to correspond to said end portions, so that the recesses open to the top edge of the bar, fitting said end portions into the recesses, so that their outer surfaces are flush with the surface of the screen, and then forcing the metal of the bar about the recesses inwardly onto the beveled edges of the end portions, so that the handle is securely attached.

For a more complete disclosure of the invention, reference is made to the following specification in connection with the accompanying drawing, in which:

Fig. 1 is a side elevation of a window screen construction embodying my invention.

Fig. 2 is a sectional view at line 2—2 of Fig. 1.

Figs. 3 to 7 are detail views illustrating different steps in the process of attaching the handle and

Fig. 8 is a detail view of a form of handle

which I employ, before application to the frame.

In Fig. 1 of the drawing, a portion of a window screen is illustrated which comprises a bottom bar *a* which, in the present instance, will preferably be of an aluminum alloy, which has been extruded thru a suitable die, so that the surface presents a smooth and finished appearance, the screen *b* being secured to the back side of the frame by pressing it into a groove and locking it therein by a wire keeper *c*, which is forced therein.

According to my invention I provide a handle *d* which preferably consists of a strip of the same material as that of which the frame is formed, said strip comprising a straight middle portion and two end portions, each of which is bent at right angles thereto and twisted thru 90°, so that the end portions *e* are both disposed flatwise with relation to the handle, the front surfaces of said end portions and the front edge of the handle proper being disposed in approximately the same plane. The end portions *e* are transversely enlarged or somewhat wider than the strip and are made circular, each forming a head of greater diameter than the width of the metal strip of which the handle is made and which thus projects at each side of the strip. The edges of said heads are beveled or recessed on their front sides, forming inclined faces *f*, and a guide hole *e'* is preferably provided at the geometrical center of each head *e*. Two shallow circular holes *g* are formed in the inner side of the bar *a*, each of which is of a depth equal to the thickness of the heads *e*, or of the metal of which the handle is made, and of a diameter equal to the diameter of said heads, said holes each being bored in such a position that a portion thereof, thru an arc of preferably approximately 90°, opens to the top edge of the bar *a*, as indicated in Fig. 3, and being spaced apart a distance equal to the distance between said heads *e*, so that the said heads may be placed in said holes and, when

in position therein, the outer sides thereof will be flush with the front side of the bar and the handle portion will project above the top edge thereof, and lie wholly in the rear of the front face of the frame. After the handle has been placed in this position, the metal at the side of each hole *g* is forced inward onto the beveled edge *f* of each head

e, so that the handle is secured to the bar in this position. This is preferably done by employing a punch *h* having a circular cutting edge *i* which is beveled on its internal side and is a slightly greater diameter than that of the holes *g*. In securing each head by this means, the punch is set in concentric relation to the head and then forced into the metal, thereby forming a circular indentation *a'*, therein and forcing the metal at the side of the hole inwardly, so that it is pressed firmly against the beveled surface of the head, and causes the latter to be firmly held against the bottom of the hole. In practice the punch may be provided with a yielding centering device *j*, which will be set into the centering recess *e'* in the head, so that the cut which is formed in the bar will be exactly concentric with the edge of the head onto which the metal is bent, thus giving the whole construction a finished and attractive appearance.

With the above described construction the head portions of the handle will not only be securely clamped against the bottom of the recess in which they are located, but the upper edge portions of the heads, which lie between a diameter thereof which is parallel to the top edge of the bar and said top edge, will engage the corresponding top side portions of the recess *g*, so that the latter will act as a shoulder to prevent the head in the recess from being pulled upward therein. Consequently, the handle is securely fastened to the bar. No portions of the handle or its securing means, therefore, projects beyond the side of the bar, and the entire construction presents a finished appearance.

By employing suitable jigs and tools in performing the above described operation the expense of forming and attaching the handle will be found to compare favorably with other methods, which might be employed.

While the foregoing description and the claims specify the application of the handle to the bottom bar of the frame, it will be understood that this is merely descriptive of the most common usage and that the invention is in no way limited to its application to any particular bar of the frame. The invention may also be employed in other relations than that disclosed and claimed.

I claim:

1. In combination with the bottom bar of a metal screen frame, a pull handle therefor

comprising a metal strip having a transversely enlarged head at one end, said bar having a recess opening to one side and to its top edge and said handle being extended into said recess from said top edge and having its head fitted therein, the metal of the bar about the recess being forced into engagement with the edge of the head, to hold it in position therein. 60

2. In combination with the bottom bar of a metal screen frame, a pull handle therefor comprising a metal strip having a flat faced, transversely enlarged head at one end, said bar having a recess therein which opens to one side and into which said head is fitted, the top side of said recess opening to the top edge of the bar, to permit the handle to be disposed in the rear of the front side of the bar, the edge of said head being recessed on its outer side and the metal of the bar about the recess therein being forced inward onto 70 said recessed edge. 75

3. In combination with the bottom bar of a metal screen frame, a pull handle therefor comprising a metal strap having a flat faced circular end portion of greater diameter than the width of the adjacent portion of the handle, said bar having a circular recess in one side thereof, corresponding to said end portion and said recess having a side opening to the top edge of the bar, said handle being 80 extended thru said opening and having its 85 said end portion fitted in said recess and the metal at the side of said recess being forced onto said end portion to hold it in position in the recess. 90

4. In combination with the bottom bar of a metal screen frame, a pull handle comprising a metal strap having a flat, circular end portion of greater diameter than the width of the adjacent portion of the handle, said bar having a circular recess in one side which opens to the top edge thereof, and is of a depth and diameter corresponding to the thickness and diameter of said end portion, said handle extending into said recess from the said top edge and having its said end portion fitted therein, so that the outer side of the handle is flush with the side of the bar, and said end portion having its edge recessed at its outer side and the metal of the bar about the recess being forced into engagement with its recessed edge. 100 105

In testimony whereof, I have signed by name to this specification.

LAURENCE M. FOSS.
